INFANT FEEDING FORK OR THE LIKE

Karl Henry Pearson, Jr., R.D. 1, Prosperity, Pa. 15329

Filed Jan. 18, 1973, Ser. No. 324,775

Term of patent 14 years

Int. Cl. D7—03

U.S. Cl. D7—141

Fig. 1

Fig. 2.

Fig. 3.

FIG. 1 is a top plan view of an infant feeding fork or the like showing my new design.

FIG. 2 is a side view thereof; and,

FIG. 3 is a bottom view thereof.

The side opposite that shown is substantially similar to that shown in FIG. 2.

I claim:

The ornamental design for an infant feeding fork or the like, substantially as shown and described.
